Primary Examiner — Mark Goodwin*(74) Attorney, Agent, or Firm* — Workman Nydegger(57) **CLAIM**

The ornamental design for a bracket for a modular panel mounting system, as shown and described.

DESCRIPTION

FIG. 1 is a front perspective view of a bracket for a modular panel mounting system;

FIG. 2 is a rear perspective view thereof;

FIG. 3 is a top view thereof;

FIG. 4 is a right elevation view thereof, of which the left elevation view is a mirror image;

FIG. 5 is a front elevation view thereof;

FIG. 6 is a rear elevation thereof; and,

FIG. 7 shows a bracket for a modular panel mounting system in an exemplary environment.
